(57) **CLAIM**

The ornamental design for a staple collation, as shown and described.

DESCRIPTION

FIG. 1 is a front perspective view of a staple collation in accordance with the first embodiment of the present invention.

FIG. 2 is a front view of the staple collation of FIG. 1.

FIG. 3 is a rear view of the staple collation of FIG. 1.

FIG. 4 is a left-side view of the staple collation of FIG. 1.

FIG. 5 is a right-side view of the staple collation of FIG. 1.

FIG. 6 is a top view of the staple collation of FIG. 1.

FIG. 7 is a bottom view of the staple collation of FIG. 1.

FIG. 8 is a front perspective view of a staple collation in accordance with the second embodiment of the present invention.

FIG. 9 is a front view of the staple collation of FIG. 8.

FIG. 10 is a rear view of the staple collation of FIG. 8.

FIG. 11 is a left-side view of the staple collation of FIG. 8.

FIG. 12 is a right-side view of the staple collation of FIG. 8.

FIG. 13 is a top view of the staple collation of FIG. 8.

FIG. 14 is a bottom view of the staple collation of FIG. 8.

FIG. 15 is a front perspective view of a staple collation in accordance with the third embodiment of the present invention.

FIG. 16 is a front view of the staple collation of FIG. 15.

FIG. 17 is a rear view of the staple collation of FIG. 15.

FIG. 18 is a left-side view of the staple collation of FIG. 15.

FIG. 19 is a right-side view of the staple collation of FIG. 15.

FIG. 20 is a top view of the staple collation of FIG. 15; and,

FIG. 21 is a bottom view of the staple collation of FIG. 15. The portions of the staple collation shown in broken lines are included for the purpose of illustrating environment and form no part of the claimed design.
